(57) **CLAIM**

The ornamental design for an interactive kiosk as shown and described.

DESCRIPTION

1. Interactive kiosk

1.1 : Perspective

1.2 : rear perspective view

1.3 : Front

1.4 : Back

1.5 : Left

1.6 : Right

1.7 : Top

1.8 : Bottom

1.9 : Reference view

1.10 : Reference view

1.11 : Reference view

The claimed design is an interactive kiosk that adjusts the direction, angle or height of the display according to the user, and has replaceable drawer-type modules; the broken lines indicate portions of the article that form no part of the claimed design; reproduction 1.9 is a reference view showing that the angle of the display is adjusted; reproduction 1.10 is a reference view showing that the display is rotated; reproduction 1.11 is a reference view showing that the display is rotated;

(Continued)

reproduction 1.11 is a reference view showing that the right side modules are opened; reproductions 1.9 to 1.11 form no part of the claimed design.

1 Claim, 11 Drawing Sheets
